UNITED STATES PATENT OFFICE.

JOHN DENIS MANSFIELD ROBINSON, OF ROYDON, ENGLAND.

MEANS FOR FACILITATING LOCOMOTION ON FOOT.

Application filed May 7, 1926, Serial No. 107,444, and in Great Britain May 18, 1925.

This invention relates to means for facilitating locomotion on foot, of the type in which an elastic apparatus connects the feet or legs of the wearer.

5 The invention comprises essentially an elastic medium or connector and improved means for attaching the same to both feet or legs of the wearer, the said elastic medium being otherwise entirely free from attachment or control so that it exerts an equal or

10 opposite pull on each foot or leg. The means of attachment for the elastic medium are preferably attached below the knee and the said elastic medium is stretched 15 or otherwise put in a state of elastic stress each time that a step is taken by the wearer.

By the use of the improved appliance it is possible to walk or run at a faster speed and with less fatigue than is possible in the 20 ordinary way.

In the accompanying drawings—

Figure 1 is a perspective view of one form of the improved appliance for facilitating locomotion on foot and

25 Figure 2 is a view showing the appliance in use.

Figure 3 is a perspective view of one of the boots of the user of the appliance, drawn to a larger scale than Figure 2, showing 30 clearly the mode of attachment of the appliance thereto.

Figure 4 is a perspective view of another form of the appliance and

35 Figure 5 is a perspective view of a portion of the appliance shown in Figure 4, illustrating a slight modification.

Figure 6 is a perspective view of another form of the appliance and

40 Figure 7 is a perspective view showing the said appliance in use.

Figure 8 is a perspective view of a portion of the appliance shown in Figures 4 or 6 illustrating a modification and

45 Figure 9 is a perspective view of this modified portion applied to a boot.

Referring to Figures 1 to 3, *a* is the elastic medium or connector for connecting together the feet *b*, *b* of the wearer. This connector is made preferably of pure solid rubber 50 cord in a single length or of a plurality of fine rubber strands covered with cotton designed to stretch with the elastic and formed at each end with loops *c*, *d*, *e* to engage under the instep, around the heel and

over the instep, respectively. The loops 55 *c*, *d*, *e* are made by engaging one end of the cord *a* with the aligned hollow arms or branches of two cross-shaped members *f* and *g* of slightly smaller internal diameter than the cord and preferably made of rubber 60 strengthened with canvas insertion. The cord is first pulled through the arms *h* and *i* of the member *f* by a string attached to one end to form the loop *c* of suitable size 65 designed to pass under the waist of one of the wearer's boots from the inner side of the said boot, or that nearest to the other foot, to the other or outer side of the said boot. The cord is then pulled through the arms 70 *j*, *k* of the member *g* to complete the loop *c* and to form the loop *d* which passes over the instep, and the cord is then passed through the remaining arms *l*, *m* of the member *f*, the said members *f* and *g* being located 75 just in front of and slightly below the ankle on opposite sides of the boot; the end of the cord is then passed through the remaining arms *n*, *o* of the member *g* to form the loop *e* designed to pass around the boot heel, the loose end of the cord being then bent back 80 on itself and fixed with a rubber ring *p*, or otherwise.

To effect the crossing of the cord *a* within the members *f* and *g*, it has to be stretched to half its diameter, and when the stretching is relieved the friction set up between the cord at the crossing points and with the sides of the tubes is sufficient to resist any displacement by the pull on the cord due to walking, at the same time the length of the loops and the portion connecting the feet together can be varied to suit different sized boots and the stride of the user by suitable tension on the cord to draw it through the members *f*, *g*.

85 The loops *c*, *d* and *e* at each end of the cord *a* may be instantly engaged with respective boots by passing each toe through a loop *d*, which is pulled on to the instep then pulling loops *c* and *e* under the arch below the instep and stretching the latter loop round the back of the heel level with the ankle. Thus a firm grip of each foot 90 is obtained and the exact position wherein the pull of the foot is exerted by the cord *a* can be adjusted to suit the wearer's gait and any habit of turning the toes abnormally inwards or outwards can be corrected.

The loops and cord are preferably blackened so as to be hardly noticeable and where trousers are worn are covered to a large extent by the bottoms thereof.

- 5 Normally for walking, the cord α is about a quarter of an inch in diameter and the unstretched length between the feet about nine inches, but the thickness of the rubber depends on the speed desired by the pedestrian and the weight of his leg and boot, the thickness necessary for running being greater than that for walking and greater for a man than a boy, whilst the length of the cord between the feet is adjusted to be 10 about one quarter of the stride of the wearer. In all the above dimensions, the extensibility of the rubber has however, to be taken into account.

In the form of the invention illustrated 20 in Figure 4, a single elastic cord α^1 is employed as in the arrangement illustrated in Figures 1 to 3, but it is connected at each end to a circular band or strap q of elastic webbing capable of adjustment around the ankle by the buckle fastening q^1 . The cord α^1 is advantageously made detachable from the said bands and for this purpose is provided with spring closing hooks r, r designed to engage with rings or loops s, s on the bands q, q ; or, the cord α^1 is provided at each end with a metal eye t , Figure 5, with which, and with the rings s , split rings u engage.

In the form of the invention illustrated in Figure 6, two elastic cords α^2, α^2 are employed instead of the single cord α to connect the feet together. For this purpose I use an endless cord or ring of about two feet in circumference connected at opposite points to the ankle bands or straps q, q with this form of the appliance, when in use, as illustrated in Figure 7, the straps q are arranged with the endless cord or ring encircling the ankles.

In Figures 8 and 9 I have shown a strap v of elastic webbing connected at its ends to approximately opposite points of the angle band q and designed to pass under the waist of the boot similarly to the loop

c , Figures 1 to 3, to prevent the said band rising up the leg of the wearer.

50

Claims:

1. An appliance for facilitating human locomotion in running or walking comprising ankle engaging members, means to prevent said ankle engaging members from rising upon the leg of the wearer and a single elastic element joining and connected only to said ankle members and adapted to be placed under tension with each stride of the wearer so as to extend in a straight line 55 between said members.

2. An appliance for facilitating human locomotion in running or walking comprising ankle bands, means connecting opposite sides of the bands and extending beneath the instep to prevent the bands from rising when in use and a single elastic element joining and connected only to said bands and having length approximately one-quarter of the stride of the wearer and adapted to be 60 placed under tension with each stride of the wearer so as to extend in a straight line 70 between said parts.

3. An appliance for facilitating human locomotion in running or walking comprising ankle bands, resilient means connecting opposite sides of each of said bands and adapted to extend beneath the waist of the foot to prevent rising of the bands in use and a single elastic cord joining and connected only to said bands and adapted to be stretched in a straight line with each 75 stride of the wearer.

4. An appliance for facilitating human locomotion in running or walking comprising elastic ankle bands, elastic members connecting opposite sides of each band and extending beneath the waist of the foot to prevent the band from rising in use and a single elastic element joining and connected 80 only to said bands, said element constructed to exert a force in a straight line direction which substantially constantly tends to force the feet together.

JOHN DENIS MANSFIELD ROBINSON.
